UNITED STATES PATENT OFFICE.

HOWARD T. MARSHALL, OF BROCKTON, MASSACHUSETTS.

BOOT OR SHOE.

SPECIFICATION forming part of Letters Patent No. 298,599, dated May 13, 1884.

Application filed June 17, 1882. (No model.)

To all whom it may concern:

Be it known that I, HOWARD T. MARSHALL, of Brockton, in the county of Plymouth and State of Massachusetts, have invented certain new and useful Improvements in Boots or Shoes, of which the following is a full, clear, and exact description.

This invention consists of a boot or shoe having an opening in its vamp or upper, which is arranged to be connected by a lacing cord or cords in the usual manner of laced boots, and has an independent elastic goring or gorings, so that the boot or shoe can be adjusted to fit the foot of the wearer by the lacing cord or cords, and when so adjusted by the elastic goring or gorings it can be put on and taken off without necessarily changing the adjustment of the lacing cord or cords, all substantially as hereinafter fully described.

20 In the accompanying plate of drawings this invention is illustrated in connection with a gaiter-boot having an elastic goring, Figure 1 being a side view of a gaiter-boot. Fig. 2 is cross-section on line 3 3, Fig. 1.

25 In the drawings, A represents the upper or vamp of a boot, which has an elastic gore-piece, a, inserted on each side, as shown, all as usual in gaiter-boots. The boot has a slitted opening, d, in the upper or vamp A, 30 which opening runs along a portion of the length, including the instep portion of the vamp or upper, and each side of the slitted opening the vamp has a series of eyeleted holes, g, which are arranged along the length 35 of such opening and receive a lacing-cord, h, passing from side to side of and across the slit, and thus lacing together its two sides.

40 h is a tongue-piece of leather inside of the boot and covering the slitted opening. This tongue is secured at either one or both of its ends or its sides to the inside of its upper in the usual manner of attaching tongues to laced boots. The slitted opening d, with the lacing-cord h, allows the boot to be loosened or tightened, as may be desired, about the foot of the

wearer after it has been put on, and thus to be adjusted and rendered the more comfortable and easy and made the better to fit the foot of the wearer, and when so adjusted, because of the otherwise ordinary formation of the elastic goring on the gaiter-boot, the boot, as is plain, can be put on and taken off without change of the adjustment of the lacing-cord, whatever such adjustment may be. The inside tongue shields and guards the foot of the wearer against the lacing-cord.

Two lacing-cords may be used as well as one, and in lieu of the holes to receive the lacing cord or cords hooks or studs may be substituted, as well known. Again, the invention herein described is applicable to shoes as well as boots.

I do not claim, broadly, a boot having lacing or button fastenings combined with an elastic gore, for such, broadly, is not new; but my invention differs therefrom in constructing the parts so that the boot can be adjusted by the fastenings, and also put on and taken off the foot without loosening the fastenings.

Having thus described my invention, what I claim, and desire to secure by Letters Patent, is—

As an improved article of manufacture, a boot or shoe made with a slitted opening in its vamp or upper arranged to be connected by a lacing cord or cords for adjusting the boot to fit the instep and around the ankle of the wearer, and having an elastic goring or gorings, and formed, all substantially as set forth, so that the boot can be adjusted to the foot and taken off and put on without disturbing the fastenings.

In testimony whereof I have hereunto set my hand in the presence of two subscribing witnesses.

HOWARD T. MARSHALL.
